STORM SHUTTER

William W. Goodman, Miami Beach, Fla.

Application October 17, 1934, Serial No. 748,680

4 Claims. (Cl. 189—64)

This invention relates to storm shutters, more particularly to shutters for use in localities where high winds, tornadoes, hurricanes and other destructive storms are of sufficiently frequent occurrence to require special protective means for windows and similar openings. It is the principal object of my invention to provide a shutter of this character which will afford an increased degree of protection together with novel means for attaching it to the sash which will hold the shutter securely in place and at the same time facilitate quick application or removal of the shutters.

A further object is the provision of fastening means which will not disfigure the appearance of the sash to which it is applied and which will not substantially interfere with the usual manipulation of the sash.

Other and further objects will be apparent from the following specification and claims.

In the accompanying drawing,

Fig. 1 is a front view of a portion of a sash with the shutter in place;

Fig. 2 is a vertical sectional view of the structure shown in Fig. 1, portions of the window framing being shown in dotted line;

Fig. 3 is a sectional view substantially on line 3—3 of Fig. 2;

Fig. 4 is a face view, on a smaller scale, of the shutter alone;

Fig. 5 is a fragmentary view, on a larger scale of the slot member of the securing means;

Fig. 6 is a view similar to Fig. 2 showing the shutter applied to a different type of sash; and

Fig. 7 is a perspective view on a smaller scale of a modified form of shutter.

Referring to the drawing, 10 indicates the shutter generally which is preferably formed of a sheet of metal, preferably steel, of suitable thickness. In Figs. 1, 2 and 3, the movable sash member is shown at 11 and the fixed sash frame at 12, the glass being indicated at 13. The sash members may be of desired size and type, the form illustrated having the sash 11 hinged to the frame 12 at 14. In Fig. 2 certain portions of the wall framing adjacent the window opening, such as the drip 15 and cross member 16 are shown in dotted line to indicate the relation of the shutter to window structure as a whole.

The shutter 10 is provided adjacent its corners with openings 18 having the general shape of an inverted keyhole. As best shown in Fig. 5 these openings comprise a circular portion 19 and an elongated, upwardly extending, portion 20, the

sides 21 of portion 20 converging slightly together.

The sash 11 is provided with bronze studs 25 threaded as at 26 into the sash. The studs are provided with heads 27 of a size to pass through the circular portion 19 of the openings 18. The shanks 28 of the studs are slightly smaller in cross-sectional diameter than the maximum width of elongated portions 20 and slightly larger than the minimum width of said slots. The 10 studs are provided with bronze hubs 30 which serve to space the shutter slightly from the sash.

In applying the shutters the latter are raised sufficiently to permit the heads 27 of the studs to pass through the circular portion 19 of the 15 openings 18 and then permitted to drop to let the shanks 28 enter the elongated portions 20 of the openings 18. Since the sides 21 of these portions are inclined to decrease the width of the openings to less than the diameter of the 20 shanks of the studs the latter are wedged into the openings as indicated at x to hold the shutter fast and prevent rattling. Preferably the material of the shank is made slightly softer than the steel of the shutter so that the edges 25 of slots 20 tend to bite into the shanks to increase the wedging action. The hubs 30 serve to hold the shutter out of direct contact with the sash thereby preventing marring of the latter and this spacing also facilitates application and 30 removal of the shutter. It will also be seen that the manner of securing the shutters to the sash permits the latter to be swung open when the sash is in place.

In Fig. 6 is shown a modified form of stud 33 35 adapted to be secured to a wooden sash 34. The inner end of studs are made in the form of wood screws 35 engaging in the sash, the head 36, shank 37 and hub 38 being exactly similar to the corresponding parts of the studs previously described, 40 and shutter 10 is positioned and held on the studs in the same manner.

In Fig. 7 is shown a shutter 40 formed of relatively light gauge material, the edges being bent up to form a flange 41 giving sufficient stiffness 45 and rigidity to the shutter to permit handling and to maintain the shape of the shutter when in position. The shutter 40 is provided with openings 42 having the same form and function as openings 19 previously described.

I claim:

1. The combination with a sash of a storm shutter which comprises a rectangular closure member formed wholly of unbreakable material and provided with a plurality of openings adjacent 55

its edges, said closure member being imperforate throughout the window protecting portion, said openings having an enlarged portion and a relatively narrow elongated upwardly extending slot portion, a plurality of studs secured to the sash and spaced to correspond with said opening, said studs having enlarged heads, adapted to pass through the enlarged portion of said openings, and shank portions engageable in said slot portion of said openings, and hubs formed on the shank of the studs, adjacent the face of the sash, to hold the closure member slightly spaced from the sash.

2. The combination with a sash of a storm shutter which comprises a rectangular closure member formed wholly of unbreakable material and provided with a plurality of openings adjacent its edges, said closure member being imperforate throughout the window protecting portion, said openings having an enlarged portion and a relatively narrow elongated upwardly extending slot portion diminishing in width toward the top, a plurality of studs secured to the sash and spaced to correspond with said openings, said studs having enlarged heads, adapted to pass through the enlarged portion of said openings, and shank portions of a size to make a wedging engagement with the sides of the slot portion of said openings, and hubs formed on the shank of the studs adjacent the face of the sash to hold the closure member slightly spaced from the sash.

3. The combination with a sash of a storm shutter which comprises a rectangular closure member formed wholly of unbreakable material and provided with a plurality of openings adjacent its edges, said closure member being imperforate throughout the window protecting portion, said openings having an enlarged portion and a rela-

tively narrow elongated upwardly extending slot portion diminishing in width toward the top, a plurality of studs secured to the sash and spaced to correspond with said openings, said studs having enlarged heads, adapted to pass through the enlarged portion of said openings, and shank portions of a size to make a wedging engagement with the sides of the slot portion of said openings, hubs formed on the shank of the studs adjacent the face of the sash to hold the closure member 10 slightly spaced from the sash, the materials of which the stud and the stud engaging edges of the slot portion of said openings are made being of differing degrees of hardness.

4. The combination with a sash of a storm 15 shutter which comprises a rectangular metal plate provided with a plurality of openings adjacent its edges, said plate being imperforate throughout the window protecting portion, said openings having an enlarged portion and an 20 elongated upwardly extending slot portion diminishing in width toward the top, a plurality of studs secured to the sash and spaced to correspond with said openings, said studs having enlarged heads, adapted to pass through the enlarged portion of 25 said openings, and shank portions having a cross sectional diameter intermediate the maximum and minimum width dimension of the slot portion of said openings in the plate whereby the shanks of the studs may be wedged in said slot 30 portions after the heads of the studs have been passed through the enlarged portions of the openings, and hubs formed on the shank of the studs, adjacent the sash to hold the plate slightly spaced from the sash, the shanks of the studs being 35 formed of slightly softer metal than the metal of the plate.

WILLIAM W. GOODMAN.
